(57) **CLAIM**

The ornamental design for a musical keyboard, as shown
and described.

DESCRIPTION

FIG. 1 is a perspective view of a musical keyboard showing
one embodiment of my new design;

FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof;
FIG. 8 is an enlarged partial sectional view of the musical
keyboard shown in FIG. 1, taken along the line 8—8 of FIG.
1;
FIG. 9 is a perspective view of the musical keyboard
showing a second embodiment of my new design, the keys
on the musical keyboard having a different shape than the
keys in the first embodiment;
FIG. 10 is an enlarged partial sectional view of the musical
keyboard shown in FIG. 9, taken along the line 10—10 of
FIG. 9.
FIG. 11 is a perspective view of a musical keyboard showing
a third embodiment of my new design, the keys being
arranged on the musical keyboard so as to be seen as a mirror
image of the keys in the first embodiment;
FIG. 12 is a front elevational view thereof;
FIG. 13 is a rear elevational view thereof;
FIG. 14 is a right side elevational view thereof;
FIG. 15 is a left side elevational view thereof;
